UNITED STATES PATENT OFFICE.

JOHN PURVIS, JR., OF CHICAGO, ILLINOIS.

FILLING MACHINE.

Application filed February 11, 1924. Serial No. 992,070.

To all whom it may concern:

Be it known that I, JOHN PURVIS, Jr., a citizen of the United States, and a resident of Chicago, in the county of Cook and State 5 of Illinois, have invented a new and useful Improvement in Filling Machines, of which the following is a full, clear, and exact description.

My invention relates to improvements in 10 filling machines, and more particularly to those machines that are designed to fill containers with fluid or semi-fluid substances, such as oils, greases, petroleum jelly, lard, etc., and it consists in the combinations, constructions, and arrangements herein described and claimed.

An object of my invention is to provide 15 a device of simple construction which is operated by pressure applied to the fluid material itself, and which will deliver a predetermined quantity of the fluid.

A further object of my invention is to 20 provide a device which can be readily adjusted to deliver varying amounts of fluid at will.

A further object of my invention is to 25 provide a device which is balanced in such a manner that it may be operated at a minimum pressure and will thus serve for filling receptacles with fluid which will not stand a high pressure.

A further object of my invention is to 30 provide a device of the type described in which the action may be controlled, i. e., hastened or retarded by a check valve placed in the pressure line.

Other objects and advantages will appear 35 in the following specification, and the novel features of the invention may be particularly pointed out in the appended claims.

My invention is illustrated in the accompanying drawings, forming part of this application, in which

Figure 1 is a sectional view through one 40 of the units,

Figure 2 is a plan view showing a plurality of units arranged in multiple, and

Figure 3 is an enlarged sectional view 45 along the line 3—3 of Figure 1, part of the pinion being shown in plan view.

In carrying out my invention I make use of a supply pipe line 1 extending from any suitable source of supply (not shown). The liquid in the pipe line 1 may be any liquid or semi-liquid, and pressure may be applied to it by any suitable pressure means. In 50

case of semi-plastic materials, such as grease, lard, etc., these materials are heated in order to bring them into a fluid condition.

Connected to the supply pipe are units 55 such as that shown in Figure 1. In this figure it will be observed that branch pipes 2 and 2' lead to valve casings 3 and 3' respectively, these valve casings being each provided with a three-way valve such as 60 those shown at 4. The valve casing 3 communicates with the bottom of a cylinder 5, the valve casing 3' communicating with a similar cylinder 5'. The cylinders 5 and 5' are associated together, and may be held 65 in spaced relation by a suitable frame such as that shown at 6 in Figure 1. Within the cylinder 5 is a piston 7, and this piston has pivotally secured thereto a rack 8.

In the cylinder 5' is a piston 7' which is 70 pivotally connected to the rack 8' similar to the rack 8. The racks 8 and 8' engage a pinion 9 which is mounted at 10 above the cylinders 5 and 5'.

The racks 8 and 8' are held in contact 75 with the pinion 9 by spring pressed blocks 11, each of which bears a roller 12. As will be seen in Figure 3, the block 12 is slidably disposed in a frame 13, carried by the support 6, this frame being slotted at 14 to 80 permit the movement of the block. A spring 15 bears on the block and the tension of the spring may be regulated by means of a screw 16.

In Figure 2 I have shown a number of 85 these units arranged in multiple and being served by a common pipe line. A return pipe 17 is provided leading to the source of supply (not shown). In this return pipe is a valve 18.

From the foregoing description of the 90 various parts of the device, the operation thereof may be readily understood. When pressure is applied to the liquid in the pipe 1, it will pass into the laterally extending pipes 2 or 2', depending upon the position of the valves 4 or 4'. Thus in Figure 1 the liquid would have passed the valve 4 and have filled the cylinder 5', pushing the piston 7' upwardly, and turning the pinion 9 95 so as to force the rack 8 downwardly and to drive the piston 7 ahead of it, thus forcing out the contents of the cylinder 5 through the open valve 4 into the receptacle 19. When the piston 7 reaches the bottom 100 of its travel, then the action will stop. A measured quantity of fluid will therefore 110

be delivered to the receptacle 19. The valves 4 and 4' are rotary valves, and are connected together by means of the arms 20 and 20', and a link 21, connecting the two arms. When it is desired to fill the other receptacle 22, it is only necessary to move the link 21 from the position shown in full lines to the right in Figure 11. This will close the valve 4' and open the valve 4, and 10 the pressure will then be exerted on the piston 7. This piston will then rise and through the medium of the pinion 9 will force the rack 8' and the piston 7' downwardly, thus forcing the contents of the cylinder 5' out into the receptacle 22.

When it is desired to change the amount of liquid delivered the upper ends of the racks 8 and 8' may be swung outwardly against the tension of the springs 15, so as to be disengaged from the pinion 9. The pistons 7 and 7' may then be moved to the proper position to deliver a predetermined amount, and the racks may then be brought into engagement with the common pinion 9.

As will be seen from Figure 2, a number of these units may be arranged in multiple to be actuated by a common supply pipe. The return pipe 17 is provided with a valve 18 so that in case it is desired to speed up the action, the valve may be turned so as to cause a back pressure, and thus tend to accelerate the action of the device.

The apparatus is simple in construction. It will be observed that each of the units is balanced, that is to say, when the fluid is admitted to one cylinder, it tends to cooperate with the fluid in the other cylinder for actuating the device, for it will be observed that as the fluid in one cylinder forces the piston up, the natural gravity of the fluid in the other cylinder will tend to cause the vacuum or decrease of pressure in the cylinder which is emptying, and this will aid in the operation of the device. Thus the device may be used for liquids which will not stand much pressure.

One advantage of the device is that the pistons always keep the cylinders clean. There is no residue of liquid clinging to the walls, which is often the case where the filling of the receptacle is accomplished by merely permitting the weight of the liquid to act. In the present device, there is a positive cleaning of the cylinders, so that they are always in condition for delivering precisely the amount at each reciprocation.

I claim:

1. The combination of a pair of cylinders, a piston for each cylinder, a three-way valve associated with each cylinder, a supply pipe communicating with each of said valves, one of said valves being open when the other is shut, a rack secured to each piston, a pinion

disposed between and engaging both racks, whereby the movement of one piston will cause the downward movement of the other piston, and spring pressed means for holding said racks in engagement with said pinion, said racks being movable against the spring tension to bring them out of engagement with said pinion at will.

2. The combination of a pair of cylinders, a piston in each cylinder, a rack having one end pivotally secured to each piston, a pinion, spring means for holding each of said racks in engagement with said pinion, a three-way valve connected at the bottom of each cylinder, a supply pipe communicating with both of said valves, means for simultaneously opening either of said valves and closing the other, and a discharge outlet communicating with each of said valves.

3. The combination of a pair of cylinders, a piston in each cylinder, a rack having one end pivotally secured to each piston, a pinion, spring means for holding each of said racks in engagement with said pinion, a three-way valve connected at the bottom of each cylinder, a supply pipe communicating with both of said valves, means for simultaneously opening either of said valves and closing the other, a discharge outlet communicating with each of said valves, a return pipe communicating with said first named pipe, and a valve in said return pipe for restricting the flow of liquid therethrough.

4. The combination with a supply pipe, of a plurality of units communicating with said supply pipe, each of said units comprising a pair of cylinders, pistons in said cylinders, a three-way valve disposed at the bottom of each cylinder communicating with said supply pipe, means connecting said pistons for translating an upward movement of one piston into a downward movement of the other piston, means for closing one valve of each unit while opening the other valve, a return pipe communicating with the supply pipe, and a valve in the return pipe for restricting the flow.

5. The combination with a supply pipe, of a plurality of units communicating with said supply pipe, each of said units comprising a pair of cylinders, pistons in said cylinders, a three-way valve disposed at the bottom of each cylinder communicating with said supply pipe, means connecting said pistons for translating an upward movement of one piston into a downward movement of the piston of its pair, means for closing one valve of each unit while opening the other valve, and means for regulating the speed of the pistons in all of said units simultaneously.

JOHN PURVIS, JR.
